GEORGE ADAM WEBER, OF STAMFORD, CONNECTICUT, ASSIGNOR TO THE WEBER RAILWAY JOINT MFG. CO., OF NEW YORK, N. Y., A CORPORATION OF WEST VIRGINIA.

RAILROAD-RAIL JOINT.

SPECIFICATION forming part of Letters Patent No. 739,462, dated September 22, 1903.

Application filed January 20, 1902, Serial No. 90,411. (No model.)

To all whom it may concern:

Be it known that I, GEORGE ADAM WEBER, of Stamford, county of Fairfield, State of Connecticut, have invented a new and useful Improvement in Railroad-Rail Joints, of which the following is a specification.

This improvement relates to joints where rail-sections are united end to end and secured together side by side in close proximity through the agency of a single joint.

In the accompanying drawings, Figure 1 is a transverse section of a railroad-rail joint embodying this improvement. Fig. 2 is a plan or top view of the same. Fig. 3 is a side view of a block comprised in the joint.

Similar letters of reference designate corresponding parts in all the figures.

A' A² designate railroad-rail sections arranged in line. B' B² designate other railroad-rail sections arranged in line. On the outer side of the rail-sections A' A² is a fish-plate C and on the outer side of the rail-sections B' B² is a fish-plate D. As here shown, these fish-plates are made in the form of channel-bars. In other words, they have flange-like portions c d extending outwardly from their top and bottom edges. They are adapted to fit upon the feet of the rail-sections with which they coat and also under the heads of those rail-sections. Intermediate the rail-sections A' A² and the rail-sections B' B² are blocks E, which are adapted to fit upon the feet and under the heads of the rail-sections. They may be made quite short in the direction of the length of the rail-sections, as illustrated in Figs. 2 and 3.

F G designate angle chairs or shoes, each having a base portion and an upright. The base portions extend below the feet of the rail-sections A' A² B' B² throughout a sufficient portion of the length of those rail-sections to form a suitable joint. Usually they and the fish-plates C D will be of the same length. It will be seen that the base of the angle shoe or chair F extends not only under the feet of the rail-sections A' A², but also partly under the feet of the rail-sections B' B², but that the base of the angle shoe or chair G extends only part way under the feet of the rail-sections B' B². Preferably these

angle chairs or shoes will be reinforced at the junctional portions of their bases and uprights.

Packing-bars H I fit against the outer sides of the fish-plates C D and bear against the opposite surfaces of the uprights of the angle chairs or shoes. They are shown as filling the spaces between the flange-like portions c d of the fish-plates C D.

Bolts J extend through the uprights of the angle shoes or chairs, the packing-bars H I, the fish-plates C D, the rail-sections A' A² B' B², and the blocks E and have heads outside the upright of one angle shoe or chair and nuts outside the upright of the other angle shoe or chair.

It will be seen that by my invention a very strong and otherwise efficient joint is produced for rail-sections to be united endwise and secured sidewise in close proximity.

The blocks E, fish-plates C D, and angle shoes or chairs F G may be made of any suitable metal, but preferably will be made of steel. The packing-bars H I will preferably be made of wood.

What I claim as new, and desire to secure by Letters Patent, is—

1. The combination with two pairs of railroad-rail sections arranged in close proximity side by side, of blocks arranged intermediate the two pairs of rail-sections, fish-plates arranged against the outside of the two pairs of rail-sections, shoe angles or chairs one having a base extending below the pairs of rail-sections, and an upright extending outside of one of the fish-plates, the upright of the other shoe-angle extending outside the other fish-plate and bolts for securing the parts together.

2. The combination with two pairs of railroad-rail sections arranged in close proximity, side by side, of blocks arranged intermediate of the two pairs of rail-sections, fish-plates arranged against the outside of the two pairs of rail-sections, angle shoes or chairs having uprights which are outside the fish-plates, and bolts for securing the parts together.

3. The combination with two pairs of railroad-rail sections arranged in close proximity, side by side, of blocks arranged intermediate of the two pairs of rail-sections, fish-plates

having flange-like portions at their upper and lower edges, packing-bars fitted to the outer sides of these fish-plates, angle shoes or chairs having uprights which are outside the fish-
5 plates, and bolts for securing the parts together.

In testimony whereof I have signed my

name to this specification in the presence of two subscribing witnesses.

GEORGE ADAM WEBER.
